H. C. MANN,
LIQUID FUEL BURNER,
APPLICATION FILED NOV. 8, 1920.

1,410,942.

Patented Mar. 28, 1922.

INVENTOR:

Harold C. Mann
By Wm Wallace White
ATTY.

UNITED STATES PATENT OFFICE.

HAROLD CORNWALLIS MANN, OF LONDON, ENGLAND, ASSIGNOR OF ONE-HALF TO THE CHEMICAL ENGINEERING AND WILTON'S PATENT FURNACE COMPANY LIMITED, OF HENDON, LONDON, ENGLAND.

LIQUID-FUEL BURNER.

1,410,942.

Specification of Letters Patent. Patented Mar. 28, 1922.

Application filed November 8, 1920. Serial No. 422,649.

To all whom it may concern:

Be it known that I, HAROLD CORNWALLIS MANN, of 48 Normanton Avenue, Wimbledon Park, London, England, a subject of the King of Great Britain and Ireland, have invented certain new and useful Improvements in or Relating to Liquid-Fuel Burners, of which the following is a specification.

This invention relates to liquid fuel burners of the type described in patent specification 22,753/1904 in which fuel air and steam pass through a central tube in the burner, the fuel being atomized by a helical blade and by a blast of steam which passes through an annular orifice at the nozzle.

The object of this invention is to provide an improved burner of this type.

According to this invention the steam, air and fuel pass into the central tube through a Venturi tube.

The drawing filed herewith is a longitudinal section of one form of burner made in accordance with this invention:—

a is a Venturi tube, *b* a steam jet, *c* a liquid fuel cup to admit fuel and air to the Venturi tube, *d* is a spreader, *e* a spiral vane around the spreader *e'*, *f* is an annular orifice for the fuel and steam. *g* is an external tube to which steam is admitted at *h*, *j j* are orifices for the steam arranged round the annular orifice *f*. *g'* is an annular chamber between the external tube and the Venturi tube.

The coned shaped spreader *e'* tends to increase the velocity of the mixture of air steam and fuel after it has passed through the Venturi construction and counteracts the loss of velocity due to the friction of the spiral vane *e*.

In use the oil being fed into the cup *c* carries with it sufficient air for the complete combustion of the fuel and the steam issuing from the jet *b* and passing round the spiral vane *e* draws the fuel along with it and atomizes it, the atomization being further effected by the coned spreader and by the steam issuing from the orifices *j j*.

This steam therefore, serves the purpose of an injection of water vapour into the flame thereby assisting the complete combustion of the fuel in the furnace by being split up by the intensity of the combustion taking place into hydrogen and carbonmonoxide, which, in its turn combines with all the unconsumed, or unburnt, particles of oil fuel which may have escaped the action of the flame when issuing from the spreader in the Venturi tube.

What I claim and desire to secure by Letters Patent is:—

In a liquid fuel burner, an external tube, a Venturi tube within the external tube and spaced therefrom to form an annular chamber between the said tubes, means for admitting fuel and air to the Venturi tube, means for admitting steam to the annular chamber, a cone-shaped spreader at the outlet end of the Venturi tube, a spiral vane around the spreader, the Venturi tube having an annular orifice surrounding the spreader and a number of passages leading from the annular chamber and disposed around the annular orifice, said passages converging at their outer ends.

In testimony whereof I have signed my name to this specification.

HAROLD CORNWALLIS MANN.
